The ornamental design for a vehicle panel instrument, as shown and described.

DESCRIPTION

FIG. 1 is front view of a vehicle panel instrument showing my new design;

FIG. 2 is a top view thereof;

FIG. 3 is a bottom view thereof;

FIG. 4 is a left front perspective view thereof;

FIG. 5 is a left side view thereof;

FIG. 6 is a rear view thereof; and,

FIG. 7 is a right side view thereof.

The dotted line showing of vehicle panel structure is for illustrative purposes only and forms no part of the claimed design.
